ULTRAVIOLET LAMP

George F. Embshoff, Hamilton County, Ohio, assignor to Institutum Divi Thome Foundation, Cincinnati, Ohio, a corporation of Ohio

Application October 1, 1948, Serial No. 52,363

4 Claims. (Cl. 315—49)

1

This invention relates to ultraviolet arc lamps and more particularly to ultraviolet lamps or burners of the type sold to the general public for use as sun lamps.

The usual method of providing ultraviolet radiation in sun lamps is to operate a mercury vapor arc in series with a suitable ballast resistance. The desirable and beneficial ultraviolet wave lengths are those longer than about 2800 Angströms, whereas shorter wave lengths may have harmful effects. Since the spectrum of the mercury arc contains substantial amounts of energy at these undesirable shorter wave lengths, the usual practice in sun lamps is to enclose the arc in glass which filters out most if not all of the radiation below about 2800 Angströms. On the other hand, as the operating temperature and vapor pressure in the arc increase, the ultraviolet energy output in the region of the desirable longer wave lengths mentioned above also increases. Hence for sun lamp purposes, it is advantageous to utilize the heat developed by the ballast resistance to increase the operating temperature of the arc and with it the vapor pressure to a value approaching atmospheric pressure as pointed out in greater detail herein-after.

It has also been a common practice to combine the arc bulb and ballast resistance in a unitary assemblage adapted for simple and easy connection to and disconnection from its base or housing as a unit. As shown in the prior U. S. Patent No. 2,369,987, for example, the opposite ends of the elongated arc bulb or tube have been inserted in ceramic sleeves, the ballast resistance wire being threaded back and forth through axially extending holes in the sleeves. However, the relatively large mass of the sleeves heated up slowly, and further it was not feasible to distribute ballast heat along the length of the arc because of the need for long sleeves specially constructed to provide windows for ultraviolet emission. Moreover, even in their simpler form shown in the prior patent, such sleeves were expensive and the time and labor required to thread the resistance wire and complete the device was excessive. Still further, in case of burning out of either the tube or the ballast, it was necessary to replace the entire assembly of tube, sleeves, and ballast.

Inasmuch as sun lamps are ordinarily used only for brief periods of 10-15 minutes, it is important to bring the arc to the desired operating temperature and vapor pressure as quickly as possible so that a substantial part of the period

2

of exposure remains in which to realize the benefits mentioned above. One of the objects of the present invention is to provide an improved arrangement of ballast resistance relative to the arc bulb which facilitates rapid heating of the bulb without interfering with the emission of ultraviolet radiation therefrom to the surrounding atmosphere.

Another object of the invention is to provide 10 the ballast resistance in the form of a unit separate from the arc tube, the latter being separately removable from and replaceable in the lamp.

A further object is to eliminate sleeves of the 15 type described above and the time and labor required to thread the ballast wire and to provide a cheaper and more effective type of ballast adapted to be installed as a separate prefabricated unit in the lamp base or housing.

Still further objects are to provide novel means 20 for mounting the tube and ballast unit and for housing and shielding the ends and electrical connections thereof, which means are simple and inexpensive, adapted for manufacture by quantity production methods and apparatus, and at the same time effective and reliable.

One embodiment of the invention has been 25 illustrated in the accompanying drawings, but it is to be expressly understood that said drawings are for purposes of illustration only and are not to be taken as a definition of the limits of the invention, reference being had to the appended claims for this purpose.

In the drawings,

30 Fig. 1 is a diagrammatic illustration of the principal elements and the circuit of a lamp suitable for the application of the invention;

Fig. 2 is a plan view, partly in section, of a 35 preferred embodiment of the invention in a lamp 40 of the type shown in Fig. 1;

Fig. 3 is a side view, partly in section, of the 45 lamp shown in Fig. 2;

Figs. 4, 5 and 6 are respectively sections on the lines 4—4, 5—5 and 6—6 of Fig. 3;

Fig. 7 is a front view of another embodiment 50 of the invention;

Fig. 8 is a side view of Fig. 7, partly in section on the center line of the device;

Fig. 9 is a section on the line 9—9 of Fig. 7; and

Fig. 10 comprises a series of curves showing 55 certain operating characteristics of a lamp embodying the invention.

The invention may be embodied in various types of lamps and by way of example thereof Fig. 1 shows diagrammatically a lamp of the

same general type as the lamp of the prior patent mentioned above. A lamp base 1 is provided near its opposite ends with supply terminals 2, 3 which preferably are of the plug-in type for convenient connection to a source of supply indicated at 4. The ballast resistance is preferably divided into two parts 5 and 6, although this division is not essential. The arc bulb 7 contains main arc electrodes 8 and 9 adjacent its opposite ends, and the ballast resistance is connected in series with the arc path between these electrodes in any suitable manner. In the form shown, this is accomplished by connecting the ends of resistance 5 to the supply terminal 2 and the electrode 8, and the ends of resistance 6 to the supply terminal 3 and the electrode 9.

To facilitate starting the arc, filaments 10 and 11 are associated with the electrodes 8 and 9 respectively, one end of each filament being connected with its associated electrode to the end of the ballast resistance 5 or 6. The other ends of the filaments 10 and 11 are connected to terminals 12 and 13 respectively, and a starting switch 14 is connected between these terminals. The starting switch may be operated manually if desired, or may be of any suitable type adapted to open automatically after a brief time period. When the starting switch is separate from the lamp unit, as in the form shown, the terminals 12, 13 are preferably of the plug-in type like the terminals 2, 3.

The arc bulb contains a quantity of vaporizable and ionizable material such as mercury, and is usually filled with argon or other suitable rare gas at a low pressure. The starting filaments 10, 11 are coated with or otherwise embody a suitable electron-emissive substance. When the lamp is connected to the supply 4, current flows through a series circuit comprising terminal 2, resistance 5, starting filament 10, terminal 12, starting switch 14, terminal 13, starting filament 11, resistance 6, and terminal 3. As the filaments become hot, electronic emission therefrom will result in ionization of the atmosphere in the arc bulb. After a brief initial period, the starting switch 14 is opened to break the series circuit described above and the main arc strikes between the electrodes 8 and 9 through the ionized atmosphere, the current then flowing in series through the arc path and the resistances 5 and 6.

Figs. 2-6, inclusive, show a practical embodiment of the invention in a lamp of the type described above with reference to Figure 1. The base 1 comprises a sheet metal plate shaped by a stamping or pressing operation to the form hereinafter described. At opposite ends, this base plate carries mounting blocks 15 and 16 of suitable insulating material, the terminals 2, 3, 12 and 13 being mounted in these blocks with their plug ends projecting below the base through openings 17 cut out of the sheet metal base plate for this purpose. The mounting blocks are secured in place by turned-up flanges of the base plate along the sides of the blocks as shown at 18 and across the ends of the blocks as shown at 19. The end flanges 19 are provided with tabs 20 turned over and pressed down on top of the mounting blocks, and preferably the end of each block is recessed centrally at 21 and a portion 22 of each end flange is bent inwardly into the recesses 21 to hold the blocks firmly.

At the inner ends of the mounting blocks, plate-like supports 23 and 24 project upwardly from the base in planes substantially at right angles to its length, being spaced apart by a dis-

tance at least co-extensive with the length of the arc path between the electrodes 8 and 9. These supports are also formed from sheet metal and are each provided with a central flange 25 turned horizontally and engaging the upper surface of the inner end of the mounting block (Figs. 3 and 6) and with tabs 26 projecting downwardly on either side of the flange 25 into engagement with the base plate 1. Additional tabs 27 extend at right angles from the vertical outer edges of the tabs 26, these tabs 27 being inside the flanges 18 of the base plate and having lugs 28 which extend down through openings in the base plate and are suitably deformed to hold the supporting plates firmly in position as shown in Figure 6.

The spaced supporting plates 23 and 24 enable the arc bulb 7 and the ballast resistances 5 and 6 to be mounted in parallel closely adjacent positions therebetween so that the entire length of the arc is exposed to emit ultraviolet radiation while at the same time the heat from the ballast resistances is distributed throughout the length of the bulb. To this end the resistances 5 and 6 are made rigid and self-supporting between the plates 23, 24, and in the form shown comprise coils of resistance wire inserted in supporting tubes 29 and 30 of heat resistant ceramic or other suitable material. These tubes heat up very rapidly to a relatively high temperature so that heat is quickly available to raise the operating temperature of the arc. The arc bulb and the tubes are quickly and easily mounted by inserting their ends in suitable openings formed in the supporting plates. Preferably the tubes 29, 30 are located between the arc bulb 7 and the base plate 1, one tube on each side of a longitudinal plane through the center lines of the arc bulb and base. The base plate may be dished upwardly between the supporting plates as indicated at 31 in order to strengthen the base plate and to provide a reflecting surface close to the tubes 29, 30 and arc bulb 7, thereby increasing the effective output of the lamp and minimizing dissipation of ballast heat to the surrounding atmosphere.

Thus the arc bulb and the resistor elements are independently mounted and are separately removable and replaceable in case of need. Installation and connection of these elements, as well as removal and replacement thereof, are facilitated by the fact that their ends are exposed beyond the supporting plates 23, 24 so that the necessary electrical connections are accessible and can easily be made or broken. In the form shown, these electrical connections correspond to the diagram of Fig. 1 in the following manner. One end of the resistance 5 is connected by a wire 32 to the supply terminal 2 to which it is anchored by a nut 33. Similarly the opposite end of the resistance 6 is connected by a wire 34 to the terminal 3 to which it is anchored by a nut 35. Suitable leads from the electrodes 8, 9 and filaments 10, 11 project outwardly through the press 36 at each end of the arc bulb. At the right-hand end of the lamp, one lead 37 of the filament 10 and both leads 38 of the electrode 8 are combined at 39 and connected at 40 to a wire 41 that leads to the end of the resistance 5. The remaining lead 42 of the filament 10 is connected to the terminal 12, and may as shown be passed through a small hole in the connecting block 16 and anchored to the terminal underneath the block, although this is not necessary. Similar connections are made at the left-hand end of the lamp, one lead 43 of the filament 11 and the two leads 44 of the electrode 9 being

combined at 45 and connected at 46 to a wire 47 leading to the end of the resistance 6. The remaining lead 48 of the filament 11 passes through a hole in the mounting block 15 and is connected underneath the block to the terminal 13.

The electrical connections at both ends of the lamp are thus readily accessible in case of need, but normally are enclosed and protected by removable metal hoods which cooperate with the ends of the base plate and with the supporting plates 23, 24 to form closed compartments around the ends of the arc bulb and ballast resistors at both ends of the lamp. These hoods are preferably made of sheet metal parts properly cut and shaped by stamping or pressing and assembled permanently in any suitable manner as by spot welding. In the form shown, each hood comprises a flat end plate 49 and a U-shaped hood member 50 having a flange 51 turned over and secured to the edge of the end plate 49 and a similar flange 52 adapted to engage over the edge of the supporting plate 23 or 24. These hoods are attached to the lamp in any suitable manner such that they can be removed quickly and easily whenever desired. In the form shown, the end plate 49 is formed with a lug 53 adapted to snap over the end flange 19 of the base plate and to engage in a notch therein, and each side of the hood member 50 has a similar lug 54 adapted to snap over and engage in notches in the side flanges 18 of the base plate. The hoods may be lined with heat resistant material such as asbestos as shown at 55 (Fig. 3), which aids in keeping the ends of the lamp hot and preventing condensation of mercury therein.

The embodiment of the invention illustrated in Figs. 7-9 is adapted to be plugged in at one end and has all four plug terminals projecting from one end instead of in pairs projecting from the side of the base as in the previous embodiment. This arrangement may be convenient for use with certain types of lamp mounts. In this case it is convenient also to connect both ballast resistances in series between one end of the arc and the supply line, instead of arranging them as described above.

Referring to Figs. 7-9, the base plate 60 and supporting plates 61, 62 correspond with and are similar to the base plate 1 and supporting plates 23, 24 of Figs. 1-6. The plates 61, 62 serve to support an arc bulb 63 containing arc electrodes 64 and starting filaments 65 near its opposite ends, as well as a pair of ballast resistor units 66, 67, which elements may also be similar to the corresponding elements of Figs. 1-6.

Instead of two mounting blocks, a single mounting block 68 is located at the lower end of the lamp in a plane at a right angle to the base plate 60 and carrying four terminals projecting from the lower end of the lamp. One pair of terminals 69, 70 on one side of the lamp (Fig. 8) serves as supply terminals. The other pair of terminals on the other side of the lamp, one of which is shown at 71, serves to connect the starting filaments to the starter switch as described above. Thus the triple lead 72 from electrode 64 and one end of filament 65 at the lower end of the lamp are connected to supply terminal 69. The corresponding triple lead 73 at the top is connected to the lower end of the resistor 66, passing for this purpose through an insulator tube 74 paralleling the resistor and mounted with it in the supporting plates 61, 62. The upper end of resistor 66 is connected at 75 with the upper end of the resistor 67, and the lower end of the latter is connected by a lead 76 to the other sup-

ply terminal 70. To complete the starting circuit, the lead 77 from the lower starting filament is connected to the front terminal 71, and the corresponding lead 78 from the upper filament passes through an insulator tube 79 similar to the tube 74 and is connected to the other terminal 71 (not shown).

The mounting block 68 is supported by a sheet metal frame or casing 80 connected to the base plate in any suitable way and preferably forming the end plate of a hood 81 enclosing the lower end of the lamp. The upper end is provided with a similar hood 82 the end plate 83 of which is domed and preferably provided with a ventilator 84.

In operation, the main arc starts when the arc bulb is relatively cool and the mercury vapor pressure is correspondingly low so that the arc first operates at relatively low voltage and high current. However, due to the heat generated in the arc itself and to the heat supplied by the ballast resistors, the operating temperature and mercury vapor pressure increase rapidly, accompanied by a corresponding increase in the voltage across the arc which is closely related to and varies with the pressure. Assuming a sufficient quantity of mercury in the bulb, the arc will stabilize at a final operating pressure and corresponding voltage the values of which will depend primarily on the amount of heat generated and the amount dissipated to the surrounding atmosphere.

The present invention relates particularly to sun lamp burners adapted to operate at the normally available household voltage of 120 volts, the length of the arc path between the electrodes being within the approximate limits of 1-3 inches. Under these conditions arc voltages, expressed either as total arc voltages or as volts per inch of length of the arc, correspond closely with definite mercury vapor pressures. Thus in lamps of this type either arc volts per inch, or the corresponding mercury vapor pressure, may be used as an index of the energy distribution of the arc which varies with operating temperature and pressure as stated above.

Fig. 10 shows the variation in the amount of energy emitted by lamps embodying the invention at representative wave lengths in the desirable ultraviolet region in relation to arc volts per inch. It will be observed that at arc voltages less than about 20 volts per inch, the amount of energy emitted in the desirable region is very small as compared with optimum operating conditions. The mercury vapor pressure corresponding to 20 volts per inch is of the order of 600 mm. of mercury. It is necessary to bring up the temperature and vapor pressure of the arc bulb to this point in order for the lamp to operate with satisfactory efficiency as a sun lamp. Moreover, it is important to reach these operating conditions as rapidly as possible since otherwise the desired benefits of the radiation to the user will be greatly decreased.

On the other hand, if the pressure in the bulb becomes too high, the arc will go out. This results when the voltage necessary to cause the arc to strike between the electrodes becomes greater than that available under the conditions prescribed above. In lamps embodying the invention and conforming to the limiting conditions stated above, the safe upper limit of arc voltage for practical purposes is about 40 volts per inch which corresponds to a mercury vapor pressure of the order of 760 mm. of mercury.

An important advantage of the above-described arrangement of the bulb and ballast is that it satisfies the operating requirements prescribed above. The amount of ballast resistance can be made small enough to provide the required voltage drop across the arc and to eliminate practically the danger of overheating to the point where the arc goes out, while at the same time the high temperature ceramic tubes and their arrangement relative to the bulb cause the tube to heat rapidly to the necessary minimum pressure. As an actual example, excellent results were obtained with an arc bulb about $1\frac{1}{4}$ inches in diameter and $5\frac{1}{2}$ inches long, the arc length between the electrodes being approximately 2 inches, and a ballast resistance of 21 ohms divided into two sections of 10.5 ohms each. The ballast resistors may suitably comprise coiled Nichrome wire inserted in thin-walled ceramic tubes. The Nichrome wire being made as small as possible and still carry the current, the temperature of the ceramic tubes was of the order of 1100° F. On a line voltage of 120 volts, this lamp operated with an arc voltage of 40-55 volts (20-22.5 volts per inch), current of 3.0-3.5 amperes, and wattage of 150-165 watts.

Fig. 10 shows the importance for sun lamp purposes of maintaining the arc voltage within the prescribed range. The importance of reaching this range as rapidly as possible will be appreciated from the following comparison of a lamp as described above with a lamp of the type shown in Patent No. 2,369,987 mentioned above. The latter required about 14 minutes to reach an arc voltage of about 35 volts and about 20 minutes to stabilize at about 37 volts. Bearing in mind that the average period of exposure to such lamps is only about 10-15 minutes, it is apparent that users of the prior lamp do not realize the benefit of its most favorable operating conditions unless it is turned on and allowed to stabilize in advance of use for a period roughly equivalent to the period of exposure itself. Moreover even after stabilization the arc voltage (37 volts = 18.5 volts per inch) was so low that the amount of energy emitted at the desirable wave lengths was sharply curtailed and unsatisfactory, as will be appreciated from Fig. 10. In contrast, the arc voltage in the lamp embodying the present invention increased very rapidly and reached 40 volts (20 volts per inch) within about six minutes, with approximately half the normal period of exposure still remaining.

The arrangement of the ballast resistance in the form of elongated elements paralleling and closely adjacent to the arc bulb throughout its length contributes materially to the realization of the above advantages, since ballast heat is thereby made available quickly and is distributed substantially uniformly throughout the length of the arc path. This desirable arrangement is facilitated by the use of the tubes 29, 30 which provide rigid self-sustaining resistor units in a simple relatively inexpensive form. The arc bulb and the resistor units can be mounted very quickly and at the same time accurately and firmly by inserting them in the openings in the supporting plates 23, 24. With the hoods removed, moreover, the electrical connections are all accessible so that the tube and resistors can be installed and connected conveniently, or any of them can be separately removed and replaced with equal ease.

The base plate, the supporting plates and the

hoods can be made cheaply in large quantities by simple sheet metal pressing or stamping operations, and can be assembled quickly and easily. The entire length of the arc is exposed between the plates 23, 24 for effective radiation, without interference from the ballast resistors which nevertheless supply heat to the arc bulb throughout its length. The hoods enclose and protect the electrical connections and thus complete a lamp unit that is relatively inexpensive but safe and convenient to use, neat and attractive in appearance, and efficient in operation.

While only one embodiment of this invention has been described and illustrated in the drawings, it will be understood that the invention is not restricted to this embodiment but is capable of various modifications and changes in the details, form and arrangement of the various parts. Reference should therefore be had to the appended claims for a definition of the limits of the invention.

What is claimed is:

1. A lamp of the type having a tubular arc bulb and an elongated ballast resistor comprising an elongated substantially flat base, a supporting plate near each end of said base extending transversely across and projecting outwardly from said base in a plane substantially at right angles thereto, aligned openings in said supporting plates through which the opposite ends of said bulb and ballast resistor project whereby they are supported in spaced substantially parallel relation with one another and with said base, lamp terminals at at least one end of said base and connections between said terminals, bulb, and resistor, and housing members one secured to and cooperating with each end of the base and the adjacent supporting plate to form therewith a compartment enclosing the ends of said bulb and resistor and certain of said connections.

2. A lamp as defined in claim 1, said housing members comprising heat insulating material for retaining heat in said compartments around the ends of said bulb.

3. A lamp as defined in claim 1 having two ballast resistors mounted in laterally spaced substantially parallel positions at substantially equal distances from said base, said bulb being mounted outwardly of said resistors with its axis in a plane passing between said resistors and through the center line of the base.

4. A lamp as defined in claim 3, a portion of said base between said supporting plates being dished outwardly adjacent said ballast resistors and forming a reflecting surface.
